UNITED STATES PATENT OFFICE

CHARLES H. BILTY, OF MILWAUKEE, WISCONSIN

LOCOMOTIVE FIRE-DOOR FASTENER

Application filed July 9, 1928. Serial No. 291,239.

My invention relates to an automatic fastening device for mechanical firebox doors, namely an automatic latch especially intended for manually operated firebox doors.

The object of my invention is to provide a safety fastening device which will prevent improper opening of the firebox door through any unforeseen pressure or conditions within the firebox, as for example the sudden release 10 of pressure resulting from a burst flue or arch tube. With firebox door latches as at present in use, the pressure within the firebox, resulting from the bursting of a flue or arch tube, is often sufficient to throw or blow 15 the firebox door open, endangering the lives of the engine crew and causing the crew to be injured or scalded by the escaping steam and boiling water.

As a result of this imminent danger, demand has been made for safety latches on the firebox doors of locomotives. My improved device is devised to meet this requirement and at the same time to provide a simple automatic fastening device which is comparatively 25 cheap to manufacture and which may be readily applied to the firebox doors of locomotives now in use with very little expense; the locking and unlocking operations being effected through proper movement of the 30 usual firebox door handle.

The objects and advantages of my invention will all be readily comprehended from the detailed description of the accompanying drawing, wherein:

Figure 1 illustrates a locomotive firebox door in elevation and provided with my improved safety locking mechanism in a locked position.

Figure 2 is a detail top plan view of a portion of the free end of the door, its operating handle and a portion of my safety lock.

Figure 3 is a detail sectional view taken substantially on the line 3-3 of Figure 1 looking in the direction of the arrows.

Figure 4 is a detail sectional view taken substantially on the line 4-4 of Figure 1 looking in the direction of the arrows.

In the particular exemplification of the invention as disclosed in the drawing where my improved safety device is shown applied

to a locomotive firebox door, the usual door frame is shown at 10 provided with the hinge-pin receiving lugs 11, 11, apertured to receive the hinge-pin 12 which also passes through the apertured door-lugs or straps 13, 13, which extend beyond one side or end of the firebox door 14. The door 14 is of general construction, being provided with the usual rotatable vent or air admitting shutter 15 which may be rotated on the pin 16 which latter also constitutes the pivot point for the usual door-handle 17.

The handle 17 extends transversely of the door, with one end having a stop lug 18 which locks the door in full open position to prevent the door swinging to closed position by the swaying of the locomotive during firing operations. The handle is provided with the extended hand grasping end or loop 19 which forms latching engagement with the latch 20. The latch member 20 comprises an outwardly disposed arm or post provided with suitable grooves or slots see Figure 2, adapted to receive the lower longitudinal edge of the handle.

The elements thus far described are of the usual construction so that further detailed description need not be entered into.

The hand grasping end 19 of the door handle 17 is shown eyeleted or formed in the nature of a loop, see Figure 2, and is provided with an elongated link 21 of predetermined length and inter-linked with the loop portion 19 of the handle 17 so as to permit the link 21 to freely ride or slide upwardly and downwardly, as is apparent from Figure 1.

The link 21 constitutes the lower end or link of a chain, shown in part at 22 in Figure 1; with the intermediate link 23, namely the link which is connected to the elongated link 21, arranged in operative relation with a fastener member 24.

The member 24 consists of a plate bifurcated at one end; with the one bifurcation 25 pivotally mounted on bolt or rivet 26 secured to the door 14; while the other or lower bifurcation 27 is adapted to pass beneath the post or pin portion 28. This post or pin 28 may constitute an integral part of a guide strap or member 29 disposed vertically, or

substantially so, and suitably secured to the door 14 by the bolts or rivet 26 and by swaging or riveting the ends of the posts or pins 28 and 30, as shown in Figure 4. By forming the posts 28 and 30 integral with the guide-strap 29, as shown, it is apparent that the guide 29 will be maintained in spaced relation with the door a distance sufficient to permit free entry of the bifurcation 27 of the member 24 between guide strap or plate 29 and the door 14. The lower part or pin 30 will also prevent the hand grasping end 19 of the handle 17 dropping down too far when out of contact with latch 20.

15 The free or outer end of member 24 is shown provided with an apertured lug 31 through which intermediate link 23 passes.

20 Link 22, which may be of any suitable size and shape, constitutes the hand grasping end or link when it is desired to operate the mechanism, namely when the firebox door is to be opened or closed.

25 With the elongated member 24 pivoted at one end, namely the upper bifurcation 25 pivotally mounted on the bolt or rivet 26, it is apparent that member 24 will swing about the rivet 26 when raised by the operator pulling upwardly on the chain consisting of links 22, 23 and 21, thus causing the lower bifurcation 27 to move out of straddling relation with pin or stud 28 of guide member 29. The guide member 29 is disposed across the door handle 17 and is so formed that the handle may seat in a groove of the latch member 20.

30 It will be understood that the member 24 is arranged in the same vertical plane as the door handle 17; and the distance between the top of handle 17 and the pin or post 28 of guide member or strap 29, with the handle 17 in the groove of latch member 20, is just sufficient to receive the lower bifurcation 27 of member 24, as shown in Figure 4 so that upward movement of the door handle 17 out of the groove in latch member 20 is impossible.

40 When it is desired to open the firebox door 14, the operator pulls upwardly on link 22, immediately causing the short intermediate link 23 to raise the free end of member 24, thereby swinging its bifurcation 27 out of the space intermediate of the pin or post 28 and the door handle 17.

45 As the lower link 21 is elongated as shown, movement of member 24 will occur before the lower end of long link 21 comes into operating relation with the loop-end 19 of the door handle 17, with the result that lifting of the door handle 17 out of the groove or recess in the latch member 20 will only take place after the member has been moved into unlocking position.

50 When it is desired to close the door, it is apparent that by gradually lowering the chain the long link 21 will allow the handle 17 to drop into the groove of latch member 20 before the short link 23 permits member 24 to

swing downwardly and permit the lower bifurcation 27 to enter the recess above the door handle 17. With the member 24 constructed and pivoted as shown and described it is obvious that this member 24 will swing into locking position through the action of gravity.

55 As is apparent from the construction, accidental opening of the firebox door is impossible as long as the member 24 is in locking position and the dangers heretofore encountered will be eliminated.

60 My improved safety fastener may be readily applied to locomotive firebox doors without alteration in their present construction while at the same time providing an automatically operating safety device whereby accidental or improper opening of the doors is made impossible; and while I believe the construction shown to be the simplest adaptation, 85 modifications in certain respects may be made without, however, departing from the spirit of my invention.

65 What I claim is:

1. A locomotive fire door fastener comprising, in combination with the pivoted horizontally disposed handle of the firebox door, a horizontally disposed member arranged above said handle and pivotally mounted at one of its ends and above its horizontal axis to automatically swing into position below its pivot point, so as to position the free end of the member in parallel contacting relation with the door handle, and means having operative relation with the member and yielding operative relation with the door handle whereby said member is swung upwardly out of locking position in advance of movement of the door handle.

70 2. A locomotive fire door fastener comprising, in combination with the horizontally disposed handle of the firebox door pivoted to swing vertically, an elongated member pivotally mounted at one end on the door above the handle in the vertical path of the handle and normally resting thereon said member being free to move independently of the handle, and means connected with the free end of said member and having yielding connection with the door handle whereby upward pull on said means will cause said member to swing vertically out of contact with the handle in advance of movement of the handle.

75 3. A locomotive fire door fastener comprising, in combination with the horizontally disposed pivoted handle of the firebox door, a member pivoted to the door above said handle to swing vertically out of the path of the handle, with a portion of the member normally depending between the pivot point and the handle so as to hold the latter against upward movement, said member having a laterally disposed extension and means operatively connected with the extension of said member and having a yielding connection with the

handle so as to move the member in advance of the handle in the door opening operation and vice versa in the door closing operation.

4. A locomotive fire door fastener comprising, in combination with the tiltably mounted door handle, a gravity controlled member pivoted on the firebox door in the upward path of the handle so as to be normally disposed between its pivot point and the handle to hold the latter against unlatching movement, and means having operative connection with the member and a yielding connection with said handle whereby the member is swung through a vertically disposed arc out of the upward path of the handle in advance of movement of said handle.

5. A locomotive fire door fastener comprising, in combination with a hinged firebox door provided with a vertically moving pivoted handle, an automatic fastener consisting of an elongated member disposed lengthwise above the handle and pivotally mounted at one end on the door, a vertical guide member for the handle and said member whereby the handle and member are maintained in vertical alignment, and means having operative connection with the outer free end of the member and yielding operative relation with the handle whereby swinging upward movement of the member is induced in advance of the handle in the door opening operation and the handle permitted to move into latching position in advance of movement of the member into fastening position in the door closing operation.
